HYDRAULIC CONTROL MEANS

Original application filed November 6, 1926, Serial No. 146,720. Divided and this application filed February 10, 1928. Serial No. 253,412.

This invention relates to improvements in hydraulic control means, and more particularly to hydraulic actuating devices adapted to be used for the control of other equipment, such as hoisting apparatus.

The specific example described constitutes a control for an automatic drum hoist.

One of the objects of my device is to provide automatic hydraulic means for controlling the winding drum of automatic hoists, whereby the bucket or skip will be hauled up to the storage bin, dumped, lowered to the loading hopper and started on its upward trip again without any attention from an attendant.

Another object of my device is to provide automatic hydraulic controlling means for a drum hoist, which provides maximum safety in operation, and which has means associated therewith for automatically stopping the drum in case the regular cycle of operation is interrupted or interfered with for any cause.

A further object of my invention is to provide means whereby the hoisting mechanism is automatically stopped whenever the pressure in the hydraulic system is, for any cause, lowered beyond a pre-determined value.

A still further object of my invention is to provide, in a hoisting mechanism of the class described, a control cylinder and piston having means for retarding the action of the piston for any pre-determined length of time and at any predetermined position of the piston.

Further objects and advantages of this invention will appear from the drawings and the description thereof, and from my co-pending application, Serial No. 146,720, filed Nov. 6, 1926, issued as Patent No. 1,766,236, June 24, 1930, of which the present subject matter is a division.

Although my invention consists largely in the construction and arrangement of parts hereinafter described and particularly pointed out in the claims, yet I do not limit my invention to the precise form or construction of parts shown or the several parts thereof, inasmuch as various alterations may be made without changing the scope of my invention.

In the drawings, Fig. 1 is a diagrammatic

showing of a preferred form of my hydraulic system; Fig. 2 is a detail elevation, partly in section, of the hydraulic operating cylinder and valve; Fig. 3 is a fragmentary detail view of my control-piston valve stem; Fig. 4 is a sectional view taken along the line 4—4 in Fig. 3; Fig. 5 is a sectional view, taken along the line 5—5 in Fig. 3; Fig. 6 is a fragmentary sectional elevation of a modified form of my valve stem and operating piston; Fig. 7 is an elevational view of a modified form of valve stem; and, Fig. 8 is a sectional elevation of a modified form of my valve ring; Fig. 9 is a plan view of a preferred safety cylinder; Fig. 10 is a sectional elevation taken along the line 9—9 in Fig. 9 and showing, in addition, the safety control rods and lever; Fig. 11 is a fragmentary view of my safety control rod and lever shown in Fig. 10, but shown in a neutral position.

The reference characters of the drawings represent like parts throughout the several views, and are the same as those appearing in my application of Serial No. 146,720. The same system of reference is used in order better to co-ordinate the subject matter of both the present and the parent applications.

It will be understood that the hydraulic operating mechanism or motor herein described is but one example or embodiment of the present invention, and that substantial changes may be made in the described construction without departing from the scope and spirit of the invention, and its underlying principles. The present example is arranged for operative connection with a control shaft, such as 52, by the movements of which a full automatic control of other mechanism, such as a drum hoist, is effected. The connections between shaft 52 and the hoisting mechanism proper form no part of the present invention, but may be made as set forth in my co-pending application, mentioned above.

The control shaft 52 may be operated by means of hand lever 53, preferably rigidly attached thereto, or it may be operated automatically by means of a preferred form of my hydraulic operating mechanism through quadrant 61 and link 62. Quadrant 61 is 10.

preferably rotatably mounted on shaft 52 and preferably engages sliding block 63 on lever 53 through notch 64. During normal automatic operation, block 63 engages notch 64 in 5 quadrant 61, and shaft 52 together with lever 53 are rotated by means of link 62.

My hydraulic operating mechanism preferably consists of an operating cylinder 68 having a double ended piston 69, adapted to 10 operate therein (see Fig. 2). A rocker arm 70, preferably having a fixed pivot 71, carried in any suitable manner by cylinder 68, is preferably employed to connect piston 69 to link 62 which operates quadrant 61. Piston 15 69 is preferably provided at each end with a working head 72 and 72', each of which heads preferably carries a sliding stem member 73 and 73' attached thereto in any suitable manner, and preferably having a fluted cross section 20 as shown in Fig. 5 with the exception of solid portion 79. 74 and 74' designate the cylinder head members for cylinder 68, preferably provided with openings 75 and 75' through which stems 73 and 73' are adapted 25 to project. End-caps 76 and 76' are preferably attached to cylinder heads 74 and 74', serving to enclose stems 73 and 73' when at the outer end of their strokes. Within the cylinder heads, and preferably adapted to 30 surround each of the stems, are annular valve rings 77 and 77', preferably held apart by means of springs 78'. These rings preferably form a close movable fit about the stems and preferably bear against the inner end 35 of the end-caps 76 and 76' and the shoulder 78 of cylinder heads 74 and 74' respectively, under the action of springs 78'. The function 40 of the inner valve ring 77' is, to co-act with a solid portion 79 (see Fig. 4) on stems 73 and 73' to close completely openings 75 and 75' at such times when the piston has moved to positions where the solid portions 79 are directly in contact with the rings 77'. By-pass valve openings 80 and 80' are 45 preferably provided in the cylinder heads so as to connect the interior of the cylinder heads with the interior of the cylinder 68 at either end. These by-pass valve openings are preferably controlled by means of adjustable 50 needle valve members 81 and 81' which may be provided with suitable lock nuts 82 for maintaining any desired adjustment. Suitable pipes 83 and 83' are preferably provided and adapted to connect the interior of each 55 of said cylinder heads 74 and 74' with a four-way valve 84. Valve 84 is connected with an inlet pipe 85, a drain pipe 86, and may be provided with a rotary valve member 87, having passages 88 and 89 therin and adapted to connect each of the cylinder head pipes 83 and 83' alternately to the inlet and to the drain. A suitable lever 90 serves to operate the valve member 87.

It will be understood that while I show a valve of the rotary type, I do not limit my-

self to the use of any particular type of valve or valves for performing these functions.

In operation, inlet pipe 85 to four-way valve 84 is connected to a suitable source of fluid under pressure, as will be described 70 later. Drain pipe 86 is connected to any suitable sump or receiving reservoir under atmospheric pressure. With the mechanism in position as shown in Fig. 2 and valve member 87 rotated so as to connect pipe 85 to 75 pipe 83', it will be seen that fluid under pressure will be applied to working face 72' of piston 69 through the fluted passages of stem 73' and through opening 75'. At the same time, pipe 83 of cylinder head 74 will be 80 connected to drain pipe 86 and the pressure on working face 72 will be reduced substantially to atmospheric. The piston 69 will therefore be moved to the left (in the figure) 85 the fluid ahead of face 72 being discharged through opening 75, the fluted passages in stem 73 and pipe 83, into drain 86. As piston 69 moves to the left it will rotate control shaft 52 in a clock-wise manner through rocker arm 70, link 62, quadrant 61 and lever 53. This movement of the control shaft may be used, for example, to stop the hoisting mechanism at either limit of its travel. If this is the case, a certain time lag is desirable for the hoist to load or unload. To 90 this end, it is necessary to retard the action of piston 69 at this point. The solid portions 79 of the stems 73 and 73' are preferably so placed that when piston 69 has moved the controls into the position referred to above, they will start to co-act with valve rings 77' to close openings 75 and 75' into the cylinder. In the preferred construction shown, the tension of springs 78' is preferably so adjusted that the pressure of the fluid being forced out of the cylinder will move the ring 77' away from shoulder 78 slightly so as to cause the solid portion 79 to coincide with ring 77', at that end of the piston which is receiving the pressure, slightly in advance of their coincidence at the discharge end. This prevents the building up of a sudden pressure at the discharge end of the piston and insures that the pressure at the pressure end will always be in excess of that at the discharge end. It will be noted in Fig. 2, that ring 77' controlling opening 75 has moved away from shoulder 78 under the action of the outgoing fluid ahead of working head 72. Once the solid portions 79 have moved into coincidence with rings 77' 100 it is evident that no further movement of piston 69 will take place unless pressure be applied in some manner to the working face. This is accomplished by means of the by-pass openings 80 and 80' controlled by needle valves 81 and 81'. By setting these valves at a pre-determined position, any amount of fluid desired may be admitted behind the 105 working face of the piston, and by this means 110

the piston is kept moving as slowly as is desired until the solid portions 79 have moved past the rings 77'. In Fig. 2 it will be seen that when the solid portion of stem 73' has begun to move into coincidence with ring 77', the opening 75' will be closed against the fluid under pressure. At almost the same time but slightly thereafter, spring 78' will move ring 77' against shoulder 78 of head 74 due to the drop in pressure of the outgoing fluid ahead of face 72. Fluid under pressure will continue to be admitted behind face 72' of piston 69, however, through bypass opening 80' and fluid will be permitted to escape from in front of face 72 through bypass opening 80. Piston 69 will continue to move, therefore, but it will move very slowly, the rate of movement being controlled by the needle valves 81 and 81'. After the solid portion 79 on stem 73' has moved past the ring 77' full volume will be admitted behind face 72' through opening 75' and piston 69 will begin to move more rapidly to the left (Fig. 2). At this instant the consequent rise in pressure ahead of face 72 will force ring 77' away from shoulder 78 of cylinder head 74 and opening 75 will be completely uncovered to permit substantially unrestricted flow of fluid out of the cylinder ahead of face 72. Movement of the piston to its extreme left hand position (Fig. 2), moves the control shaft 52 in a clockwise direction, for example, to start the operation of the hoist. When the skip or bucket of the hoist has reached the end of its travel, suitable mechanism (not shown), serves to move a lever 90 to actuate a four-way valve 84 to the dotted position in Fig. 2. A suitable operating control for valve 84 may be seen by reference to my co-pending application referred to above. The described movement of the valve 84 connects a pressure inlet pipe 85 to a cylinder head pipe 83 of cylinder head 74, and connects a drain pipe 86 to pipe 83' of cylinder head 74'. The piston 69 now moves to the right, (Fig. 2) with an effect on control shaft 52 similar to that described above, except that the movement is reversed, with respect to directions of motion. The described provision for a "neutral" position, a time-lag, or loading or unloading interval of a hoist, may be made during each direction of piston movement. It is usually advisable that the motion of piston 69, once a reverse pressure is applied thereto, is very rapid, and that the retarded motion of the piston through neutral may be made as slowly as desired. The various movements of the piston and the time periods thereof, may obviously be regulated to suit the requirements of the mechanism to be controlled by shaft 52, or its equivalent.

In Fig. 6 I show a modified form of my valve stem 73. In this form I prefer to attach the valve stem to the working face 72

by means of a threaded portion 205 adapted to be screwed into a tapped hole 205' in the working face, and held in any desired position by any suitable means such as lock nut 206. It will thus be seen that the relative position of the valve stem may be adjusted with respect to the piston and that the retarding action as described above, due to the co-action of solid portion 79 and valve rings 77', may be made to occur at any desired position of the piston. By providing my valve stems with a plurality of solid portions 79 it is evident that I may secure the above described retarding action at a plurality of positions of the piston. In Fig. 7 I show a form of my valve stem having two such solid portions 79 and it is evident that any number may be employed.

From an examination of Fig. 8 showing a modified form of my valve ring 77', it will be seen that by varying the dimension "X" of the valve ring, I may vary the length of time it will take for solid portion 79 to move past the valve ring, and therefore vary the period of retardation of the piston. This would permit a variation of the period of retardation for any given setting of the bypass valves described above, since for any given setting of the by-pass valve, the greater the dimension "X", the greater will be the period of retardation.

While I show a valve ring 77' adapted to co-act with the solid portion or portions 79 on the valve stems, I may eliminate the ring member 77' entirely by proportioning the valve stem and the openings 75 and 75' such that the stem makes a tight moving fit in the opening. Such a construction would operate just as effectively to close openings 75 and 75' at the desired times, but would require more accurate machine work in aligning the piston and valve stems with the cylinder heads. The elimination of the valve rings 77' would not, however, make my invention inoperative in any sense.

When the described hydraulic operating mechanism is utilized for the control of automatic machinery of any kind, for example an automatic hoist, it is advisable to make provision for an emergency, such as failure of pressure, for any reason, in the hydraulic system. Such provision is made in the present instance, by a safety mechanism, a preferred form of which appears in Figs. 9, 10 and 11. The connections, and relation to the shaft 52 appear in Fig. 1.

The safety mechanism comprises a cylinder member 125, supported suitably on a base 20. The cylinder is provided with a head member 126 having an opening 127 therein, which is arranged for connection with the source of fluid pressure through pipe 128, as herein-after described. A tubular member 129 is provided at the other end of cylinder 125 and carries a telescoping cap 130 adapted to

make a close fit with the outside surface of member 129, but capable of lateral movement with respect thereto. Cap 130 is provided with lugs 131 on each side, adapted to 5 take the threaded ends of bolts 132. The heads of these bolts are adapted to bear against flange 133 of head 126, and the function of the bolts is to maintain the relative position of cap 130 and member 129. It 10 will be seen that as bolts 132 are screwed into lugs 131, cap 130 will be moved to the left along member 129 (Fig. 10) thereby serving as a simple and positive means for adjusting the compression of a resilient member, 15 such as spring 134 adapted to operate within the chamber 135 formed by member 129 and the inner surface of cap 130. Spring 134 is adapted to operate between the inside end of cap 130 and a piston 136, to force the 20 piston to the left in cylinder 125 (Fig. 10). Piston 136 preferably carries a piston rod 137 which projects through opening 138 in cap 130 and is supported at its free end by means of any suitable bearing member 139. 25 The compression of spring 134 is so adjusted, by means of bolts 132, that when the fluid pressure within cylinder 125 ahead of piston 136 falls below a pre-determined value, the spring will move the piston 136 and rod 137 30 to its extreme-head-end position shown by dotted lines in Fig. 10. The compression is such, however, that when the fluid pressure in the hydraulic system reaches a predetermined value, the consequent pressure upon 35 piston 136 through the agency of pipe connection 128 will force the piston to the right against the pressure of spring 134 to the position shown in full lines in Fig. 10.

Piston rod 137 has a cross head 140 attached thereto in any suitable manner and adapted to carry pivot pins 141. Rods 142 are preferably attached to cross head 140 by means of the pins 141 and are provided at their opposite ends with slotted members 45 143, within which rollers 144, at either end of double-ended lever 145, are adapted to operate. Lever 145 may be secured to control shaft 52, either by a key, or through some suitable form of clutch, (not shown), to permit 50 disengagement of the safety mechanism when manual operation of the control shaft is desired.

The operation of my described form of safety device will be readily seen by an examination of Figs. 9, 10 and 11. When the mechanism is operating normally, and full pressure is maintained in the hydraulic system, piston 136 and rod 137 will occupy substantially the position shown in Fig. 10. Rods 60 142 will therefore have substantially the position shown with respect to lever 145 and it will be seen that, due to the pivoted mountings of rods 142 and the length of the slots in members 143, lever 145 may be rotated 65 either clockwise or counter-clockwise with

control shaft 52 during normal operation. This is shown by the dotted positions of lever 145 in Fig. 10. Should the hydraulic pressure in the system fall below a pre-determined pressure, for any reason, spring 134 70 will move piston 136 and rod 137 to the left in Fig. 10 until slotted members 143 have reached the position with respect to lever 145 and rollers 144, shown in Fig. 11. Due to the fact that cross head 140 is rigidly held on rod 137, the effect of the left-hand movement of rod 137 will always be to move lever 145 to the vertical position shown. This is evident from an examination of the dotted positions of lever 145 shown in Fig. 11. Any 80 other position of lever 145 than the one shown in full lines, would evidently require either a pivoted movement of collar 140 on rod 137, or a shortening of one of the rods 142 and a lengthening of the other rod 142. Since 85 the construction is such as to make this impossible, the effect of a drop in pressure in the hydraulic system will always move lever 145 to a vertical position. Since lever 145 is preferably so connected to control shaft 52 that 90 when the lever is in a vertical position, the shaft is so set that all controls are in neutral, it is evident that a drop in pressure in the hydraulic system, for any reason, will immediately and automatically set all controls 95 in neutral and stop the hoist or other equipment.

The major parts of the hydraulic system have been described in detail above, preceding the following descriptive matter relating to 100 the pressure supply means and the fluid connecting conduits. The last mentioned description will be more readily understood when presented in this order.

A preferred arrangement of my hydraulic 105 system is shown in Fig. 1. In this figure, 156 denotes a pump of any suitable type adapted to be driven from a suitable source of power. Pump 156 is connected at its suction side by means of pipe 159 to a fluid reservoir 110 160. The pressure side of pump 156 is connected by means of pipe 161 to the pressure pipe 85. Pipe 85, as described above, is connected at one end to the four-way control valve 84, and it is preferably connected at the 115 other end to the base 162 of an accumulator, whose function it is to maintain a constant pressure in the hydraulic system. The pressure accumulator may be of any suitable type, a number of which are well known in the art. 120

Pressure pipe 85 is connected to a safety pressure system 177 by means of a feeder pipe 178 and cut-off pressure pipe 179. Piping 177 is connected to pressure release valve 117 at one end, and at the other end to each end of operating cylinder 68 through one-way check valves 178'; so that if for any reason the pressure at either end of piston 68 rises momentarily above the normal pressure in the system, this increase in pressure will be re- 125 130

lieved through these check valves, and fluid will flow from the cylinder into the safety pressure system until normal pressure is restored. Pipe 128 to the safety cylinder 125, is connected to pipe 177, as shown, so that cylinder 125 will be at normal operating pressure at all times, as described above. Pressure release valve 117 is connected at its outlet opening (not shown) to drain pipe 86 by means of pipe 86', so that if valve 117 is opened, as explained above, the pressure in pipe 177, and consequently in pipe 85, will drop to atmospheric, and the safety cylinder 125 will return all controls to neutral and stop the driven mechanism. Pipe 86' provides for the return of fluid to the system through pipes 86 and 176.

As a means for cutting-off the pressure to the control valve 84, and consequently, to the control cylinder 68, immediately the pressure release valve 117 operates, I prefer to insert a cut-off valve 180 in the pressure pipe 85. Valve 180, which may be of any suitable construction, is controlled by means of a stem 181, a lever 182 pivoted at 183 and attached at 184 to a plunger rod 185. A suitable adjusting weight 186 is also attached to the free end of lever 182. Plunger rod 185 may be operated by any suitable form of plunger (not shown) working in cylinder 187 and connected to the safety pressure system through pipe 179. It will be seen that as the fluid pressure is built up in the pressure and safety systems, the plunger (not shown) in cylinder 187 will be forced upward, under the action of this pressure, thereby opening valve 180 against the action of weight 186. As soon, however, as pressure release valve 117 releases the pressure in the system, weight 186 will close valve 180, thereby permitting the pressure in both ends of cylinder 68 to drop to atmospheric. Thus when safety cylinder 125 returns the controls to neutral, it will not have to move piston 69 against a pressure, and the setting of shaft 52 will not be retarded.

In operation, it will be seen that as soon as pump 156 is operated, it will begin to build up a fluid pressure in the main pressure pipe 85 and safety pressure pipe 177, which pressure is maintained at substantially a constant value by means of the accumulator. As soon as this fluid pressure is built up, cut-off valve 180 opens and the mechanism is ready for operation. If, for any reason, release valve 117 is tripped the pressure in the safety system will at once fall to zero, cut-off valve 180 will close, and safety cylinder 125 will act to set the controls in neutral and stop the driven mechanism, such as a hoist. The hoist cannot be controlled again by means of the hydraulic system until release valve 117 is set by hand to its closed position, and until the fluid pressure has had sufficient time to re-set safety cylinder 125 in its normal running position

through the restricted feeder pipe 178 and open cut-off valve 180.

From the above description of parts and their operation, it will be seen that I have provided a complete hydraulic control system, susceptible of a variety of modifications for different uses, the essential features of which may be employed for direct actuation of certain types of apparatus, as well as for effecting an automatic control thereof.

I claim:

1. In a hydraulic control system, a cylinder having a fluid supply opening therein, a piston in said cylinder, a fluid valve assembly for said cylinder comprising a supply valve member carried by said piston said member having a passage extended into the cylinder, and a valve portion fixedly spaced from the piston face and a second valve member having an opening therein adapted to receive said first named valve member, said valve members coacting to open and close said supply opening.

2. In a hydraulic control system, a cylinder having a fluid supply opening in one of its walls, and a piston in said cylinder, a fluid supply valve assembly for said cylinder comprising a valve member adapted to be actuated by said piston and including a valve portion fixedly spaced from the piston face, a spring pressed valve ring adapted to receive and co-act with said valve portion to control the passage of fluid through the opening in said cylinder.

3. In a fluid operated mechanism, a double-ended operating cylinder having a fluid supply opening at each end thereof, a piston having a working face at each end thereof and adapted to operate in said cylinder, means for the selective application of fluid pressure to said working faces through said openings, and supply valve members carried by opposite ends of the piston and fixedly spaced relative to each other, said members adapted for controlling admission of fluid through said openings.

4. In a fluid actuated mechanism, a double-ended operating cylinder having a fluid supply opening at each end thereof, a piston having a working face at each end thereof and adapted to operate in said cylinder, means external to the cylinder, for the selective application of fluid pressure to said faces, a movably disposed valve seat for each of said supply openings, and valve members carried by said faces each equally and fixedly spaced therefrom and adapted to coact with said valve seats for substantially closing said openings at a pre-determined position of the piston.

5. In a hydraulic actuating mechanism, a cylinder having an opening in a wall thereof, a fluid-operated piston in said cylinder, a longitudinally grooved rod constituting a valve element secured to the piston, and hav-

ing a portion of even diameter, said rod extending through said opening and said even portion adapted to serve as a closure for said opening.

6. In a hydraulic actuating mechanism, a cylinder having a fluid supply opening in a wall thereof, a fluid actuated piston in said cylinder, a valve element affixed to the piston and having an obstructed channel therein, means coacting with the obstructed channel and adapted periodically to close said opening, and means adapted to regulate the duration of such periodical closure.

7. In a fluid operated motor, a piston, a cylinder having a fluid supply port therein, closure means for the port, including a rod member secured to the piston, and extending through said port, the rod having portions of different cross section, an auxiliary port, adapted to admit fluid to supplement the flow through said supply port, and means associated with the auxiliary port adapted to control the movement of fluid therethrough.

8. In a hydraulic motor, a cylinder, a fluid supply port therein, a piston therein, and means for retarding the supply of fluid to the piston between limits of its travel, said means including a pair of valve elements, one of the elements having an aperture there- 30 in adapted to receive the other element, whereby said elements are adapted to coact to close said supply port, one of the elements being affixed in spaced relation to the piston,

9. In a hydraulic motor, a cylinder having a fluid supply port, a piston operable in the cylinder, and means for retarding the supply of fluid to the piston for a predetermined period between limits of its travel, said means comprising a rod member affixed to the piston, a pair of valve elements carried by the rod member and movable into coincidence adjacent said port; and means for regulating said period of retardation of the piston.

10. In a hydraulic motor, a cylinder having an inlet port, a piston operable in the cylinder, and means for arresting the movement of the piston for a predetermined period between its limits of travel, said means including a valve having a closure element arranged to reciprocate with the piston and a resiliently positioned, apertured member carried and adapted for actuation by said element, the member and element coacting to constitute a closure for the inlet port.

11. A hydraulic motor comprising a cylinder, a piston operable therein, means forming a port for admitting fluid to the cylinder, and means, including an element affixed to the piston, an apertured member carried by the element and yieldably positioned adjacent said admission port, said member adapted to be moved by said element into registration with a portion thereof, whereby to

vary the volume of fluid admitted to the cylinder at a predetermined intermediate position of the piston.

12. In a hydraulic motor, a cylinder, a piston having opposed operating faces, means external to the cylinder for periodically supplying a fluid pressure to each face of the piston, a pair of valves internal to the cylinder, adapted to coact with each other to provide a period of retarded movement of the piston between its limits of travel; one of said valves comprising a valve-member carried by the piston and a spring-pressed ring providing a seat for said valve member, the other of said valves comprising an adjustable port, adapted to admit a reduced volume of working fluid when said first named valve is closed.

13. In a fluid pressure mechanism, an operating cylinder, a piston adapted to move therein, a passage for supplying fluid to said cylinder, and means actuated by said piston for automatically varying the quantity of fluid admitted through said passage, said means including a rod member having a portion of relatively enlarged cross section, and a spring pressed sleeve member, each of said members arranged for movement by the piston, one of said members being affixed to the piston, and carrying the other member, said members adapted for relative movement, one along another to control admission of fluid through said passage.

14. In a hydraulic motor, adapted for operation at variable speeds in predetermined cycles, an operating cylinder having a piston adapted to move therein, a main inlet port arranged to supply fluid to the cylinder during the major portion of the cycle of operation, and an auxiliary inlet port, for supplying fluid to said cylinder during operation of the motor at relatively reduced speeds, means including an element affixed to said piston for automatically varying the rate of flow of fluid through said main port into said cylinder, and means for regulating the supply of fluid through the auxiliary port, during periods of reduced flow through said main port.

15. In a hydraulic control device, a fluid operated piston motor including a cylinder having a main inlet port, a valve for the main port including an element secured to the piston, and provided with a portion arranged to obstruct said port and reduce the rate of piston movement in an intermediate portion of its path, an auxiliary inlet port, arranged to supply fluid to said cylinder independently of the main port, and an adjustable valve for regulating flow through the auxiliary port, whereby said valves are adapted conjointly to control inlet fluid movement.

FREDERICK N. WHITESELL.
